UNITED STATES PATENT OFFICE.

ARTHUR S. GILMAN, OF CLEVELAND, OHIO.

RIBBON FOR TYPEWRITING MACHINES.

Application filed July 14, 1921. Serial No. 484,537.

To all whom it may concern:

Be it known that I, ARTHUR S. GILMAN, a citizen of the United States, resident of Cleveland, county of Cuyahoga and State 5 of Ohio, have invented new and useful Improvements in Ribbons for Typewriting Machines, of which the following is a specification, the principle of the invention being herein explained, and the best mode in 10 15 which I have contemplated applying that principle, so as to distinguish it from other inventions.

My invention relates to means adapted for use in connection with duplicating typewriting machines and particularly to that 15 part thereof which relates to the specific device used for producing the duplication of the typewritten matter, and ordinarily referred to as the "ribbon mechanism."

20 The object of the invention is to provide means of the above described character which is simple in construction and efficient in its operation.

Said invention consists of means herein- 25 after fully described and particularly set forth in the claims.

More specifically my invention includes the provision at one end of a carbon ribbon, of a permanently secured device which may 30 be readily attached to or detached from a suitable support, the other end of such ribbon having permanently affixed thereto, elastic means to which is also secured permanently, a fastening device similar to that 35 attached to the other end of such ribbon. My invention furthermore contemplates the provision of a multiplicity of equal lengths of ribbon to which the fastening devices and the elastic member are secured as above de-

40 scribed. Furthermore, my invention includes the provision of a detachable frame adapted to be mounted upon a typewriter forming a support for and upon which a ribbon of the above described character is 45 detachably mounted, which frame is also provided with a cutting edge whereby, forms to which typewritten matter has been added, may be severed from a continuous sheet of forms, known in the trade as "superfold" forms, such as are shown and de- 50 scribed in Patent No. 1,368,729, issued February 15th, 1921, to The A. S. Gilman printing Company.

The annexed drawings and the following 55 description set forth in detail certain means embodying my invention, the described

means however, constituting but one of the various mechanical forms in which the principle of the invention may be applied.

In said annexed drawings:

Figure 1 represents a plan of a standard Underwood typewriter to which my invention has been applied.

Figure 2 represents a side elevation of such typewriter.

Figure 3 represents a fragmentary front elevation, with the ordinary ribbon broken away to disclose the auxiliary or duplicating ribbon forming a part of my invention, the view being taken from the plane indicated by line III—III, Figure 2, and in the direction indicated by the arrows.

Figure 4 represents, upon an enlarged scale, a section taken upon a plane indicated by the line IV—IV, Figure 1.

Figure 5 represents a perspective view of the auxiliary frame and ribbon mounted thereon.

Figure 6 represents a perspective view of the form of ribbon forming part of my invention and detached from its supporting and detachable frame.

Figure 7 represents a section taken upon the plane indicated by line VII—VII, Figure 5, and showing the parts of the ribbon in position prior to its final adjustment to the frame.

Figure 8 represents a view similar to that in Figure 7, with the ribbon in its operative position on the supporting frame.

The illustrated embodiment of my invention includes a frame 1, Figure 5, to which is attached a ribbon 2 of a construction hereinafter fully described.

The frame 1 is of general rectangular form 95 preferably of sheet metal, and its side members are each provided with a lug 3 forming open-ended slots 4—4 which are adapted to detachably engage a transverse bar 19 of an Underwood typewriter, which bar forms 100 a standard part of the latter.

These side members are furthermore provided with two open-ended slots 5—5 which are adapted to receive the platen spindle 6 of the typewriter. The width of the frame 105 1 is such that it will span the upper portion of the typewriter and permit the slots 4—4 and 5—5 to simultaneously engage the bar 5 and spindle 6 respectively, as shown in Figure 1. When so engaging these parts the 110 front member 7 of the frame lies above and in front of the axis of the platen, as shown

in Figure 4. This front member, consists of a flat plate, which in said position, occupies an upright position and its upper rear edge 8 forms a cutting edge for the superfold 6 strips 9, of paper, upon which the forms are printed and to which typewritten matter is added.

The side members of the frame are each provided with a downwardly extending arm 10—10, which, when the frame is mounted upon the typewriter, lie opposite and adjacent to the ends of the platen, as shown in Figure 3. To the front and near the lower end of each of these arms is formed a small 15 rectangular aperture 11 as shown clearly in Figures 2, 7 and 8.

The ribbon member 12 consists of a multiplicity of substantially equal and superposed lengths of carbon ribbon, to the ends 20 of which is secured a clip 13 preferably of thin sheet metal which is provided with a hook 14. This clip is bent around so as to enclose the ends of the ribbon lengths and is fastened permanently in that position by 25 any suitable means, preferably by indenting. The other ends of the ribbon lengths are all permanently secured preferably by sewing, to a band 15 made of elastic material, such as a woven fabric of rubber-bands 30 covered with fiber, ordinarily referred to as "elastic." Secured to the free end of this elastic band 15 is a clip 16 similar in construction to the clip 13 and preferably secured to the band in the same above-described 35 manner. The length of the ribbon structure above described is such, that it will be shorter than the distance between the arms 10. The hooks of the clips 13 and 16 are adapted to engage the arms 10—10 by 40 passing through the aperture 11, as shown in Figure 8, and to effect this engagement, the one hook 14 is first inserted into the one aperture 11 whereupon the clip 16 is grasped and the band 15 is stretched until the hook 45 17 may be brought into the position shown in Figure 7, so that upon its release it may engage the other aperture 11, as shown in Figure 8.

The length and position of the arms 50 10—10 are such that when the ribbon member is in the above described position, it will lie in front of the platen, as shown in Figure 4 and directly behind the ribbon 18 which is regularly and ordinarily supplied 55 with a typewriting machine of this character. With the auxiliary ribbon in this position, the sheets of paper are threaded between each two adjacent ribbon elements, including the ribbon 18, as shown in Figure 4. 60 In the drawings, I have shown my auxiliary ribbon device to include two ribbon elements or lengths, but it will be readily understood that as many of these lengths may be provided as are necessary to produce the 65 number of duplications that may be re-

quired. A ribbon of two lengths is suitable for producing two duplicates or carbon copies, the foremost or regular ribbon 18 producing the original of the typewritten matter, as will be readily understood by 70 those skilled in the art.

Insofar as relates to the provision of a permanently secured clip at one end of the ribbon member, and a permanently secured elastic band and a clip permanently secured 75 to the latter, at the other end, my invention is not confined to a multiplicity of ribbon elements or lengths, but may be applied to a single element.

In forming the ribbon member of my invention, separate ribbon lengths may be provided or a single length of ribbon may be folded to provide the required number of lengths, and the clips and elastic bands secured at the folds, all as will be readily understood. Care should, however, be taken that in either event the ribbon elements be of substantially the same length from the one point of fastening to the other, so that, when it is stretched into position, the lengths 90 will be subjected substantially to the same tension.

It will be noted that the slots 11 in the arms 10 of the rectangular frame extend in the same direction with the axis of the 95 platen and also are coincident with the line of strain upon the supplemental ribbons 2. The clips which are affixed to the ends of the supplemental ribbons are substantially U-shape in form and the parallel portions 100 thereof lie snugly against the front edges of the arms and the forward walls of the slots 11, while the connecting portion between these parallel parts lies in contact with the outer faces of the arms. The clip 105 is thus secured on three sides and canting or possible deflection is avoided. Such casual deflection or non-alignment of the clips would result in the failure to accurately position the supplemental ribbons and to hold them not only relatively to the type but also 110 relatively to the paper and to the surface of the platen.

In this manner, I provide a very simple and effective ribbon mechanism for producing 115 duplicate copies of typewritten matter and especially adapted for use in connection with what I have heretofore referred to as "superfold" forms.

What I claim is:

1. In combination with a typewriter, a rectangular open frame secured to the typewriter and having arms depending at the front side portions of the frame and at the ends of the platen, said arms having slots 125 near their forward ends extending in the same direction as the axis of the platen, a supplemental ribbon carried by said arms and in front of the platen, clips secured to the ends of the supplemental ribbon and 130

- having front portions adapted to rest against the forward edges of said arms, lateral and rearwardly directed portions lying against the outside faces of the arms, and
- 5 inwardly directed free end portions projecting from the rear end of the lateral portions and being adapted to enter the slots and to fit snugly against the forward walls of such slots.
- 10 2. In combination with a typewriter, a rectangular open frame removably attached to the typewriter carriage and being movable therewith, means adapted to interlock with bars of the typewriter carriage to prevent the forward, rearward and upward movement of the frame, arms depending at the front sides of the frame and lying beyond the ends of the platen, said arms having lateral slots extending through the forward portions thereof, the front edges of the arms extending slightly beyond the periphery of the platen, a series of supplemental ribbons, an elastic secured at one end of the supplemental ribbons, a clip secured to the elastic, and a second clip secured at the opposite ends of the supplemental ribbons, said clips each comprising
- forward portions extending in alignment with the ribbons, lateral portions directed rearwardly and rear portions extending inwardly from the lateral portions, said rear portions adapted to seat within the slots and to fit up against the forward walls of the slots, said lateral portions adapted to seat against the outer side faces of the arms and
- 30 the front portions of the clips adapted to rest against the forward edges of the arms, said clips being bound in place by the action of the elastic.
3. A device of the character described comprising a substantially rectangular open frame adapted to removably fit over the carriage of a typewriter, means depending from the sides of said frame for looping about the rods of the typewriter carriage whereby to support and interlock the frame upon the carriage, and arms extending downwardly from the forward portions of the frame and at the ends of the typewriter platen, said arms adapted to receive a ribbon, substantially as described.

Signed by me this 28th day of June, 1921.

ARTHUR S. GILMAN.
